ROBERT GORDON, OF PEORIA, NEW YORK.

Design No. 4,276, dated August 9, 1870.

DESIGN FOR A SPOOL-STAND.

The Schedule referred to in these Letters Patent and making part of the same

To all whom it may concern:

Be it known that I, ROBERT GORDON, of Peoria, in the county of Wyoming and State of New York, have invented or produced a new and original Design for Spool-Stand, of which the following is a specification.

Nature of the Invention.

This invention consists of a spool-stand, formed in successive steps or platforms for the reception of the spools, one tier above another, and made either stationary or revolving, as may be desired.

General Description.

A B C are the successive steps or platforms composing the stand, gradually decreasing in diameter from bottom to top, thereby producing in general outline a conical or pyramidal form.

The horizontal face of each step or platform is of the proper width to receive a series of spools placed thereon, and the vertical face is of the height necessary for them to rest against.

The vertical sides are provided with a series of corrugations, a a.

The corrugations of one step or platform alternate with those of the next, so that the spools rest upon the swells of the horizontal part and in the grooves of the vertical part.

An ornamental top, D, of any suitable kind, is provided, and if the stand is made to revolve it rests on a spindle of a base, E.

p p are ornamental notches in the steps.

The spools are held by an elastic cord, G, fig. 2, passing through bearings b b.

What I claim, and desire to secure by Letters Patent, is—

The design for a spool-stand, as herein shown and described.

In witness whereof I have hereunto signed my name in the presence of two subscribing witnesses.

ROBERT GORDON.
